CLAIM

We claim the ornamental design for a remote pull handle, substantially as shown and described.

DESCRIPTION

FIG. 1 is a perspective of the remote pull handle of the present invention.

FIG. 2 is a top plan view thereof, the undisclosed bottom is not part of the claimed design;

FIG. 3 is a side elevational view thereof;

FIG. 4 is an opposite side elevational view thereof;

FIG. 5 is an end elevational view thereof; and,

FIG. 6 is an opposite end elevational view thereof.

The broken lines are included for the purpose of illustration and form no part of the claimed design.
